UNITED STATES PATENT OFFICE.

JOSEPH F. JOY, OF PITTSBURGH, PENNSYLVANIA, ASSIGNOR TO JOY MACHINE COMPANY, OF PITTSBURGH, PENNSYLVANIA, A CORPORATION OF DELAWARE.

METHOD OF BLASTING AND APPARATUS THEREFOR.

Application filed January 24, 1924. Serial No. 688,185.

To all whom it may concern:

Be it known that JOSEPH F. Joy, a citizen of the United States, residing at Pittsburgh, in the county of Allegheny and State of Pennsylvania, has invented certain new and useful Improvements in Methods of Blasting and Apparatus Therefor, of which the following is a specification.

This invention relates to a certain new and improved method of blasting and apparatus therefor, particularly useful in the mining of coal.

The primary object of the invention is to greatly reduce the hazards of mining through the elimination of the use of blasting powder.

Another object is to so disrupt the coal as to produce a larger percentage of lump coal and a smaller percentage of fine coal and dust, without the production of smoke, whereby a better quality of coal is produced and mine atmosphere is made more healthful.

With the above general objects in view, and others that will become apparent as the nature of the invention is understood, the same consists of the novel method and apparatus hereinafter more fully described, shown in the accompanying drawing, and claimed.

In the drawing, wherein like reference characters indicate corresponding parts throughout the several views.

Figure 1 is a side elevational view of one form of apparatus constructed in accordance with the present invention, partly broken away and illustrating its use in a mine room,

Figure 2 is an enlarged fragmentary detail view, partly in side elevation and partly in section, showing the blasting nozzle in the drill hole, and

Figure 3 is a diagrammatic plan view illustrating the tanks, pumps, and pipe connections thereto,

Fig. 4 is a longitudinal section through a check-valve which is interposed in the air line leading to the blasting nozzle.

In the mining of coal, it is customary to undercut the same as at —5— for a depth substantially equal to the width of the vein, after which a hole is drilled into the coal at an angle and at one or more places above the undercut as at —6—. In order to win this cut of coal, or to dislodge and disrupt the same sufficiently to allow its removal, it has here-

tofore been customary to place an explosive charge in the drill holes and then ignite the same, thus producing considerable smoke, often reducing a large percentage of the coal to fine or small particles and lumps, and 60 making the occurrence of destructive mine fires and explosions a hazard which is necessarily incurred.

In accordance with my invention the undercut is usually made, although in some cases it may be eliminated, and the shot holes —6— are then drilled. The initial rent or fracture is then made in the coal by building up a non-expansive fluid pressure in the shot holes, and as soon as this initial rent occurs a previously accumulated charge of expansive fluid under pressure, through automatic provisions, is permitted to flow into the rents or crevices created by the high pressure non-expansive fluid and, expanding therein, 70 creates what may be termed an "artificial explosion." When the latter occurs, the coal is sufficiently shattered, loosened and broken to allow its ready removal, and no smoke or fire and very little fine coal is produced. 80

A simple form of apparatus for carrying out the above method is shown in the drawing and preferably embodies a portable machine which may be readily moved from place to place. This machine, as shown, consists of a wheeled truck —7— adapted to run on the rails —8— usually laid in the mine, which truck has an air compressor —9— and a hydraulic pump —10— mounted thereon. An electric motor —11— is 90 mounted on the truck between the air compressor and the hydraulic pump and is operatively connected to said compressor and the pump by means of suitable gearing —12— and —13—, respectively. A hydraulic reservoir —14— is mounted beside the pump —10— and the inlet of said pump is connected to the reservoir —14— as at —15—. A large air storage tank —16— is mounted beside pump —9— and motor —11—, and the pump —9— discharges into this tank —16— through the pipe —17—.

The outlet —18— of the pump —10— is connected to the reservoir —14— by a piping —19— in which is placed a manually 105 closed cut-off valve —31—, which valve is of a well-known type. The discharge line —21— connects with the outlet —18— and extends to the forward end of the truck where it is provided with a cut-off valve 110

—22—. The tank —16— has an outlet —23— at its forward end which is provided with a cut-off valve —24—.

A pressure hose —25— is coupled with the outlet of tank —16—, while a high pressure hose —26— is coupled to the discharge line —21— and to the lateral branch of a T-fitting —27—. The inner end of a long bell-mouth nozzle or tube —28— is coupled to the fitting —27— and the remaining port of the latter is connected to the hose —25— by means of a conventional check valve —29—. As the hose —26— terminates forwardly of the valve —29—, the latter will be closed by the hydraulic pressure ahead of the same in the nozzle —28— but will be opened by the lesser pressure in the air hose —25— when the hydraulic pressure is relieved, as will presently become apparent.

20 In operation valve —31— is opened, the motor —11— is started and the valves —22— and —24— are closed, thereby causing the tank —16— to be filled with air under pressure. The nozzle —28— is then inserted into the hole —6— and securely packed as at —30— by suitable packing material. Valves —22— and —24— are now opened and valve —31— closed and the non-expansile fluid passes through the discharge line —21— into nozzle —28— and into the hole —6— ahead of said nozzle. The continued operation of pump —10— results in a high pressure of non-expansile fluid being built up in the hole —6— until an initial rent or fracture —32— occurs in the coal. It is to be understood, of course, that the high pressure of the non-expansile fluid ahead of the check valve —29—, at this time, results in maintaining the check valve —29— closed. As soon as this initial rent or fracture occurs, the pressure ahead of check valve —29— is reduced and the latter is forced open, permitting the expansile fluid accumulated in tank —16— to rush through nozzle —28— into the coal, creating an effect which may be termed "an artificial explosion", whereby the coal is sufficiently broken and shattered to permit its ready removal.

50 From the foregoing description it will be seen that the invention resides primarily in the use of a non-expansile fluid for creating an initial rent or fracture, followed by the use of an expansile fluid of a lower pressure which acts upon the enlarged cavity resulting from the initial rent. It is also apparent that the initial use of a non-expansile fluid, such as water, serves to seal the pores in the strata for reducing the leakage of air or expansile fluid that is subsequently used. Furthermore, it is well-known that it is highly desirable to moisten coal dust in the mines, and it is apparent that this result is obtained from

strata being impregnated to such an extent as to prevent the occurrence of floating coal dust in the mine.

I do not wish to be understood as confining my method or apparatus to the sole 70 and specific purpose of mining coal since it is equally applicable to, and efficient in, the blasting or disintegration of many other deposits of matter that is to be disrupted and broken up to facilitate its dislodgement 75 or removal.

What I claim as new is:—

1. In an apparatus for blasting material in which a hole is drilled, means including a pump to build up a hydraulic pressure in 80 the hole sufficiently to cause an initial rent or fracture in the material, and means including a second pump to supply air under pressure into the rent upon occurrence of the latter.

2. An apparatus for blasting material comprising a nozzle adapted to be placed in a hole formed in the material and to receive a packing therearound when so placed, a portable truck having hydraulic pressure building means and air compressing means mounted thereon, flexible water and air conduits connecting said nozzle to said pressure building means and said air compressing means, and means to control the flow of the 95 water and air to said conduits.

3. An apparatus for blasting material comprising a nozzle adapted to be placed in a hole formed in the material and to receive a packing therearound when so placed, a portable truck having hydraulic pressure building means and air compressing means mounted thereon, flexible water and air conduits connecting said nozzle to said pressure building means and said air compressing means, means to control the flow of the water and air to said conduits, and a forwardly-opening check valve between the nozzle and the air conduit and rearwardly of the connection of the water conduit to the nozzle. 110

4. In an apparatus for blasting material, a nozzle adapted to be placed in a hole formed in such material and to be placed in substantially air-tight relation to the wall of said hole, means to supply a substantially non-expansile fluid under pressure into the hole through said nozzle, and means to supply an expansile fluid under pressure behind said non-expansile fluid. 115

5. In an apparatus for blasting material, a nozzle adapted to be placed in a hole formed in such material and to be placed in substantially air-tight relation to the wall of said hole, means to supply a substantially non-expansile fluid under pressure into the hole through said nozzle, and means to supply an expansile fluid under pressure behind said non-expansile fluid, and a portable support for both said fluid supplying means. 120

65 130

6. In an apparatus for blasting material, a nozzle adapted to be placed in a hole formed in such material and to be placed in substantially air-tight relation to the wall of said hole, means to supply a substantially non-expansible fluid under pressure into the hole through said nozzle, and means to supply an expansible fluid under pressure behind said non-expansible fluid, and a portable support for both said fluid supplying means, said fluid supplying means including a flexible conduit connected to the nozzle and extending from the portable support.
- 5 7. The herein-described method of blast-
- ing deposits of material which comprises 15 the following steps: providing expansive space adjacent the mass to be blasted, drilling into said mass, injecting a non-compressible fluid under pressure into the hole so drilled, continuing such injection to build 20 up the resulting pressure until rupture of the adjacent mass is effected, then releasing into the mass so ruptured, a compressed expansible fluid whereby further rupture of said mass is produced. 25

In testimony whereof I hereunto affix my signature.

JOSEPH F. JOY.
